1 Claim

ABSTRACT OF THE DISCLOSURE

Marks are placed on sound track negative in correspondence with transition between scenes on corresponding preprint film to control lighting during printing on raw stock.

This invention relates to methods and apparatus for printing on raw stock film from a preprint film in association with photographic printing techniques.

In the printing of motion picture film it is customary practice to use a single preprint film for the production of a multitude of films suitable for use in motion picture projectors. This requires that a preprint film be employed to print upon a plurality of raw stock films.

The preprint film will ordinarily include therein a sequence of scenes, each possibly having different optimum printing parameters. For example, one scene may require a greater lighting amplitude or more red or more of any specific color in order to provide the finest end product after the printing technique has been effected.

To achieve the finest end product, it is conventional to inspect the preprint film and to record the optimum printing parameters for each scene. It is also conventional in employing the thusly inspected preprint film in a printing operation to employ this recorded information to set up the optimum printing parameters for each particular scene as the printing operation is being effected.

Continuous printing operations are known in which the automatic control of the optimum printing parameters is effected through the use of various devices. For example, it is known to put edge notches directly on the preprint film to indicate the transition from one scene to another, whereupon new optimum printing parameters are set up by automatic apparatus. Metal clips are also now conventionally employed for purposes of R.F. cuing, these indicia being placed directly on the film employed in the printing operation.

It is an object of the invention to eliminate the edge notching of preprint film while nevertheless providing a very advantageous technique in respect of indicating the transition between scenes on the preprint film for purposes of controlling optimum printing parameters.

In so eliminating this edge notching, the invention avoids the weakening effect which is inherent in this technique of providing scene indicia on preprint film. Moreover, as will be shown, the invention advantageously provides for minimizing the handling of the preprint film in such a manner as to increase the longevity thereof. As will also become apparent, the invention provides for the elimination of the need for complicated electronic apparatus which provides for time delays essential to synchronizing the detection of scene transition indicia with the passage of the various scenes through a printing zone.

In addition to the above, the invention also provides for eliminating the R.F. cuing techniques which have been found undesirable in many respects. As will also appear, the invention tends to eliminate the criticality of the previously employed edge notching techniques, especially as regards A and B printing where the different

2

types of materials employed have different shrinkage rates which render the printing operations inaccurate.

As will also appear from the description which follows hereinafter, the invention provides for the possibility of storing information other than merely the indicia of a transition of scenes. Still further it will appear that the indicia of the invention are provided in such a manner as to be capable of lasting longer and therefore the new technique avoids the need for constantly replacing the film or other such material on which the indicia are stored.

Still further the invention eliminates the possible lack of synchronization between a picture film and the associated sound track, both of which are originally present in the form of preprint material and are cooperatively transferred to raw stock by techniques which are conventional and well known.

As will moreover become apparent, the invention facilitates the reverse driving of preprint material and the synchronization therewith with the raw stock being printed upon and as well facilitates the synchronization of the preprint material with the raw stock in the event that the reversed drive printing technique is employed.

To achieve the above and other of its objectives and advantages the invention proposes a method of printing on raw stock film from a preprint film having therein a sequence of scenes having different optimum printing parameters, said method comprising indicating the transitions of one scene to another by the use of indicia on a further film which is separate from the first said preprint film, such indicia being employed to initiate adjustment of the optimum printing parameters for each scene. More particularly, the invention proposes that this further film be the preprint sound track film which is employed in association with the first said preprint film so that it is not necessary to provide an extra film having no utility although it is possible within the scope of the invention to provide a dummy film if the same is required.

At the same time apparatus is provided in accordance with the invention comprising means for transporting raw stock film through a printing zone and means for transporting a preprint film through this printing zone in synchronization with the raw stock film, the preprint film having therein scenes having different optimum printing parameters and a further film being provided having indicia therein to indicate the transition between the scenes in the aforesaid preprint film. There is then provided examining means to examine this further film for the aforesaid indicia and controllable printing means responsive to the examining means to establish the optimum printing parameter for each scene at the printing zone.

The invention will next be explained with reference to a preferred embodiment thereof as illustrated in the accompanying drawing, in which:

FIG. 1 is a diagram showing a complete printing apparatus in which the technique of the invention is employed;

FIG. 2 diagrammatically illustrates the use of two preprint films in connection with a raw stock film in accordance with the invention; and

FIG. 3 illustrates a device for synchronizing the starting of the two preprint films as is required in accordance with the techniques of the invention.

In FIG. 1 is indicated a source 10 of a preprint film 12 which may be transported in one of two directions indicated by arrow 14 to or from a take-up 16. The preprint film 12 may be a negative having a sequence of scenes thereon each of which will have an optimum set of printing parameters such as, for example, intensity of light or of the various colors involved in the scene. Devices for

providing such printing parameters are well known and involve the use of interchangeable intercepting light filters or the like. The details of this equipment form no part of the instant invention.

Also illustrated in FIG. 1 is a source 18 of a raw stock film 20 which is fed in either of two directions indicated by arrow 22, either to or from a take-up device 24. The raw stock film 20 may be, for example, any positive film which is light sensitive and upon which scenes from the preprint film 12 are to be printed in frame-by-frame optical relationship. The raw stock film 20 passes in optical juxtaposition to the preprint film 12 in the vicinity of controllable printing apparatus 26 which is effective to define a first printing zone.

It is conventional in printing techniques of the aforesaid type to provide a second printing zone at which a sound track preprint film is employed. A source 28 of a sound track preprint film 30 is illustrated in FIG. 1 along with a take-up 32, the sound track film being transportable in either of two directions indicated by arrow 34 through a second printing zone defined by printing apparatus 36.

The first and second printing zones are spaced apart at some determinable distance and provision is made for transporting both of preprint films 12 and 30 through their respective printing zones in synchronism with the raw stock 20 and in such relationship with each other and with the raw stock film that a sound track is printed on the raw stock film in compatible and precise relationship with the sequence of scenes which is printed from the preprint film 12.

In accordance with the invention and as will be shown in greater detail hereinafter, indicia are provided on the sound track preprint film 30 which are effective to indicate relative to preprint film 12 when there is a transition between scenes appearing on the latter preprint film. In addition there is provided an indicia examining means 38 which inspects the indicia on film 30 and transmits an electronic signal via line 40 to the controllable printing apparatus 26 to indicate when a transition between scenes on the film 12 is occurring. The controllable printing apparatus 26 then makes adjustments in the lighting or color or such by various means, the details of which may be conventional and are too well known to warrant explanation in this text, so that the optimum printing parameters or conditions are established for the printing operation being effected in the first printing zone.

In FIG. 2 the raw stock film is indicated at 42 and it is juxtaposed to a preprint film 44 at a first printing zone indicated at 46. The preprint film 44 is a negative film having a sequence of frames 48 thereon which in well known manner constitutes a sequence of changing scenes. In FIG. 2 preprint film 44 is taken from the source 50 and is transported to zone 46 to the take-up 52. The film 44 is provided with a synchronization hole 54 cooperating with a synchronization device 56, the details of which will be explained in greater detail hereinafter.

In FIG. 2 is also indicated at 58 the second printing zone through which the sound track negative or preprint film 60 is transported while passing from a source 62 to a take-up 64. The sound track in film 60 is indicated diagrammatically at 66. At the same time there are shown by way of illustration two slots or slits 68 and 70 which constitute some of the indicia referred to hereinabove.

Slots 68 and 70 are transversely displaced relative to film 60. This is to indicate that, for example, two series of indicia may be provided, one being employed for one direction of transport of raw stock 42 and the other for the reverse direction of transport of raw stock 42 or rather the replacement of the latter after the first raw stock film has been printed upon. Stated otherwise, in order to save time the films 44 and 60 are run first in one direction and then in the opposite direction through their respective printing zones, a new raw stock film 42 being provided for each direction of running off of the preprint films. The

two sets of indicia are provided for reasons which will become hereinafter apparent.

Sprocket holes are shown for transporting the various films in well-known manner. Conventionally, there will be four holes per frame for 35 mm. film along both side edges thereof and two holes per frame for 16 mm. film along one side edge thereof.

An indicia detector 72 is diagrammatically illustrated in FIG. 2. This may take the form of a photoelectric detecting device of known type or else may be constituted by one or more microswitches or the like. One detecting means 74 or 76 is provided for the respective series of indicia.

It will be appreciated that the detecting means 72 cannot be conveniently located directly at the printing zone. For this reason it is spaced from the printing zone and accordingly a delay must be effected so as to coordinate the positions of the indicia with the corresponding transition zones on the film 44. In conventional techniques this delay is usually provided by means of complicated electronic apparatus. However, since it is quite easy to position the indicia means on the sound track on which the useful information is limited to a relatively small area, the necessary delays for either direction of running of the preprint films can be provided by placing indicia 68 and 70 in staggered relationship so that changes will be made by the controllable printing apparatus at the precise time when a transition between scenes occurs on the film 44 and this may be readily accomplished without the need for the provision of electronic delays or the like.

Films 44 and 60 also appear in FIG. 3, in which is illustrated by way of example apparatus for assuring that the two films are started in synchronism so that not only is the sound track well coordinated with the photographic information of film 44 but furthermore the proper indicating of transition points is precisely established.

More particularly there is illustrated in FIG. 3 solenoids 80 and 82 which are used at the commencement of the printing operation. Prior to this commencement holes 54 (noted above) and 84 are respectively provided in preprint films 44 and 60 indicating where the films should be started in order to achieve the necessary co-ordination between the preprint films and the raw stock film.

To commence operation solenoids 80 and 82 are operated to elevate plungers 86 and 88, which when raised, serve to provide guides onto which the films 44 and 60 are hooked by means of holes 54 and 84. When the holes 54 and 84 are respectively engaged over plungers 86 and 88, films 44 and 60 are in proper position to commence the printing operation. Thereafter solenoids 80 and 82 are deactivated and plungers 86 and 88 are depressed thereby to operate microswitches 90 and 92. Switches 90 and 92 are integrated into the machine start circuit 94 so that none of the driving apparatus of the printing device can be started until the microswitches 90 and 92 are operated. As a result, it is impossible to start a printing operation until the films 44 and 60 have been synchronized for commencing the operation.

As stated hereinabove, the invention avoids the use of edge notching or R.F. cues or the like on the film 44, the indicia being provided on a second film, preferably a sound track preprint film as illustrated in the form of preprint film 60. The invention thus contemplates a method of printing on a raw stock film from a preprint film having therein a sequence of scenes having different optimum printing parameters, said method comprising indicating the transition of one scene to another by the use of indicia on a further film so that adjustment can be made to the optimum printing parameters for each scene.

It will be also noted hereinabove that the raw stock and preprint films are cooperatively transported through a printing zone at the same speed to effect a continuous

printing operation, the further film, notably the sound track preprint film being transported at the same speed through its respective printing zone and being examined for the indicia thereon to determine when printing parameter changes may be necessary.

The invention further provides that the indicia be properly offset to account for the spacing of the examining zone from the printing zone and moreover provides for two series of indicia or more if required to facilitate running the preprint films in reverse directions. It is also clear that the invention provides for synchronizing the starting of the two preprint films to account for the relationship of the preprint films to each other and to the raw stock film.

While emphasis has been placed upon the method aspect of the invention, the invention is by no means limited to methods and is directed as well to the apparatus. This apparatus may comprise means for transporting raw stock film through a printing zone, means for transporting a preprint film through said zone, in synchronism with the raw stock film, and a further film having indicia therein to indicate the transition between scenes in the first said preprint film. There will then be incorporated into this apparatus examining means to examine the further film, preferably a sound track preprint film, for the aforesaid indicia, and controllable printing means responsive to the examining means to establish the optimum printing parameters for each scene at the printing zone. Once again the details of this controllable printing means is conventional and well known to those skilled in the art and need not be further detailed in this text.

There will now be obvious to those skilled in the art many modifications and variations of the methods and apparatus set forth above. These modifications and variations will not depart from the scope of the invention if defined by the following claim.

What is claimed is:

1. A method of printing on raw stock from a preprint film wherein is disposed a sequence of scenes having different optimum printing parameters and from a sound

track negative separate from the preprint film and having a sound track related to said scenes and a salvage area adjacent the sound track, said method comprising placing indicia in the salvage area of the sound track negative at positions corresponding to positions on the preprint film to indicate the transition between scenes on the preprint film, transporting the preprint film and sound track negative from respective sources through separate printing zones to respective take ups and then reversing the preprint film and sound track negative to return the same to the respective sources and printing onto raw stock in said printing zones during both directions of movement of the preprint film and sound track negative there-through, examining the sound track negative for said indicia at an examining zone which is spaced from the associated printing zone and the indicia being offset on the sound track negative to account for the spacing of the examining zone, adjusting the printing of the scenes in accordance with said indicia, said method further comprising arranging the indicia in two sets respectively related to each direction of travel of the sound track negative and staggering the sets to account for the differences of direction in relation to the spacing between the examining zone and corresponding printing zone.
